UNITED STATES PATENT OFFICE.

EDMUND G. HOFFMANN, OF BURKSVILLE, ILLINOIS.

ELECTRIC TIME-SWITCH.

1,282,578.

Specification of Letters Patent. Patented Oct. 22, 1918.

Application filed February 19, 1916. Serial No. 79,421.

To all whom it may concern:

Be it known that I, EDMUND G. HOFFMANN, a citizen of the United States, residing at Burksville, in the county of Monroe 5 and State of Illinois, have invented certain new and useful Improvements in Electric Time-Switches; and I do hereby declare the following to be a full, clear, and exact description of the invention, such as will enable 10 others skilled in the art to which it appertains to make and use the same.

The invention relates to improvements in electric time switches.

The object of the present invention is to 15 improve the construction of electric switches and to provide a simple, practical and efficient time switch of comparatively inexpensive construction adapted to automatically break and close an electric circuit at 20 intervals for operating various forms of electrical devices during a certain portion or portions of a day.

A further object of the invention is to provide an electric time switch of this character 25 adapted to operate continuously and equipped with means for controlling the current to an electric sign or other device for illuminating the same during the night time or a portion thereof and for extinguishing 30 the sign during the day time, said means being capable of closing and breaking the electric circuit at varying intervals to correspond with the varying lengths of the night during different seasons of the year.

With these and other objects in view the invention consists in the construction and novel combination and arrangement of parts hereinafter fully described, illustrated in the accompanying drawings and pointed out in 40 the claims hereto appended, it being understood that various changes in the form, proportion and minor details of construction may be resorted to without departing from the spirit or sacrificing any of the advantages of the invention.

In the drawings—

Figure 1 is a front elevation of an electric time switch constructed in accordance with this invention,

Fig. 2 is a side elevation of the same,

Fig. 3 is a rear elevation of the electric time signal,

Fig. 4 is a plan view or diagram of the periphery of the cylinder illustrating the arrangement of the insulating and conducting areas of the spirally grooved periphery.

Fig. 5 is an enlarged detail sectional view illustrating the manner of mounting the contact member which carries the needle.

Fig. 6 is an enlarged plan view partly in section illustrating the manner of mounting the contact member which travels in the spirally arranged grooves of the cylinder.

Fig. 7 is a plan view of a portion of the switch.

65

Like numerals of reference designate corresponding parts in the several figures of the drawings.

In the accompanying drawings in which is illustrated the preferred embodiment of the invention, 1 designates a rotary cylinder constituting a contact member and consisting of a cylindrical body portion and heads 2 and 3 and mounted on a horizontally disposed rotary spindle 4 which is journaled in suitable bearings of standards 5 and 6. The standards 5 and 6 rise from a supporting base 7 and the spindle is connected with a suitable clock motor 8 which in practice is designed to be constructed to run for a relatively long time with a single winding. Any suitable clock motor may of course be employed and as the particular construction of the clock motor does not constitute any portion of the present invention, detail illustration thereof is deemed unnecessary. The spindle and the cylinder are designed to be rotated once every 24 hours and the head or end 2 of the cylinder is provided with a dial or clock face 9 of a twenty-four hour clock, 80 and the said dial may have the hour designations arranged in two separate sets or series of one to twelve as shown, but they may be arranged in any other desired manner.

95 The rotary cylinder is provided in its periphery with spirally arranged grooves 10, which in practice will be 365 in number to correspond with the number of days of the year so that the electric time signal will require adjustment only at the end of the year. The outer face of the cylindrical body portion of the cylinder is provided with conducting and insulated areas 11 and 12 and the spirally arranged grooves which constitute a track receive a needle or point 13 of a contact member 14. The contact member 14 which is mounted on a nut 15 is caused to traverse the cylinder by a spirally grooved shaft 16 and the said contact member which is located at a point above the cylinder is equipped with an adjustable 100 105 110

weight 17 having a set screw 18 and adapted to be moved longitudinally of the contact member 14 to maintain the needle or point of the contact member in proper electrical engagement with the spirally grooved surface of the cylinder. By this construction, a proper electrical contact is produced between the rotary contact member and the transversely movable contact member 14.

10 The shaft 16 which is horizontally disposed is journaled in suitable bearings of the said standards 5 and 6 and it is provided with grooves of spiral form corresponding with the spiral grooves of the cylinder and the 15 said shaft or screw 16 makes one revolution each time, the rotary cylinder makes one revolution and it is connected with the cylinder by a train of gears for this purpose. The train of gears preferably consists of 20 upper, lower and intermediate wheels 19, 20 and 21 of proper diameters to secure this result.

Each of the spirally arranged grooves traverses the conducting and insulating 25 areas to close a circuit during a portion of each day and also to break the circuit and maintain the same in an open condition during a portion of each day.

In Fig. 4 of the drawings is shown a diagram of the conducting and insulating areas which extend over the spirally arranged grooves of the twelve months of the year, certain of the grooves being omitted for convenience of illustration. In the diagrammatic view of Fig. 4 the irregular line 22 indicates the sunrise line and marks the boundaries of the conducting and insulating areas at one side of the insulating area 12 and the irregular line 23 at the other side of 40 the insulating area indicates the sunset line. While the conducting and insulating areas are shown in the accompanying drawings for closing the electrical circuit at sun down and maintaining the electrical circuit closed during the night time and opening the circuit at sunrise, the insulating and conducting areas may be arranged in various other ways as will be readily apparent and the construction may be utilized 45 for opening and closing the electrical circuit at intervals of varying durations. The standard 5 supports an hour hand 24 which is located in line with the point or needle 13 so that the needle will indicate the 55 correct time with the hand in order to indicate whether the switch is running properly and on time. The rotary cylinder is provided at its front face at the front dial 9 with a rotary ring 25 which is connected 60 by an arm or portion 26 with the conducting portion 11 and the said conducting ring is engaged by a brush 27 preferably consisting of a spring and connected with one of the wires 28 of the electric circuit. The current passes from the wire 28

to the conducting portion 11 of the cylinder and through the contact member 14 and the shaft which is insulated from the gearing and also from the standards 5 and 6 in any suitable manner. The rotary cam or screw 70 is provided at the front end with a rotary contact ring 29 which is engaged by a brush 30 that is connected with the other wire 31 of the electric circuit. The wires 31 and 28 are designed to be connected to a suitable 75 source of current supply and the electrical device to be operated and it will be clear that when the needle of the contact member 14 is traveling in the grooves and the conducting area of the cylinder, the circuit will be 80 closed and the electrical device will be operated and that as soon as the needle through the rotary movement of the cylinder is carried into the insulating area, the circuit will be broken and maintained open until the 85 needle again engages with the conducting surface. When the cylinder is rotated, rotary motion will be communicated to the horizontal spirally grooved shaft or screw and as the upper and lower gears 19 and 20 90 are of the same diameter the cylinder and the screw will be caused to make one complete revolution in the same period of time and the nut which carries the contact member 14 will be moved longitudinally of the screw 95 or shaft 16 to cause the contact member 14 to traverse the cylinder from one end of the series of spirally arranged grooves to the other, and it will be apparent that if the cylinder makes one revolution in twenty- 100 four hours, it will require one year to move the contact member from one end of a series of spirally arranged grooves to the other when such series contains a groove for each day in the year. Also it will be clear that 105 by varying the insulating and conducting areas, the circuit may be maintained closed during the desired portion of the day and opened and closed at the exact time each day and that the electric time switch is entirely 110 automatic, it being only necessary to rewind the actuating motor at intervals. Also instead of employing an ordinary front motor electrically operated means for rewinding the motor may be used so that the device will 115 be entirely automatic and will not require attention until the end of the year. Any suitable means may be provided for enabling the nut to be quickly transferred from one end of the screw to the other as for instance 120 the nut may be made in sections detachably bolted or otherwise secured together as indicated in Fig. 5 of the drawings.

What is claimed is:—

1. An electric switch of the class described 125 including a rotary cylinder provided with spirally arranged grooves and having insulated and conducting areas at the said grooves, a shaft arranged in parallelism with the cylinder and having threads correspond- 130

- ing with the grooves of the cylinder, means for rotating the shaft and the cylinder in unison, a nut engaged by a threaded shaft and a contact member carried by the nut and having an engaging portion arranged to run in the grooves of the cylinder and an adjustable weight mounted on the contact member of the nut and movable from the said nut.
- 10 2. An electric switch of the class described including a rotary cylinder provided with spirally arranged grooves and having insulated and conducting areas at the said grooves, a shaft arranged in parallelism 30 with the cylinder and having threads corresponding with the grooves of the cylinder, means for rotating the shaft and cylinder in unison, means mounted on the threaded shaft for movement on the same, an arm carried by said means and overlying the cylinder, a contact member carried by the arm and having an engaging portion arranged to fit in the grooves of the cylinder, and a weight mounted on the arm as and for the 35 purpose specified.
- 15 3. An electric switch of the class described including a rotary cylinder provided with spirally arranged grooves and having insulated and conducting areas at the said grooves, a shaft arranged in parallelism 30 with the cylinder and having threads corresponding with the grooves of the cylinder, means for rotating the shaft and the cylinder in unison, a nut engaged by a threaded shaft and a contact member carried by the 35 nut and having an engaging portion arranged to run in the grooves of the cylinder, a contact ring mounted on the cylinder at one end thereof and electrically connected with the conducting area of the cylinder, a 40 second rotary contact ring mounted on the shaft, brushes engaging the contact ring and conductors connected with the brushes.

In testimony whereof I affix my signature in presence of two witnesses.

EDMUND G. HOFFMANN.
